US0D1096166S

(12) United States Design Patent (10) Patent No.: US D1,096,166 S
(45) Date of Patent: * Oct. 7, 2025

(54) CONTAINER

(71) Applicant: ShenZhen YiHong Holding Group Co., LTD, Guangdong (CN)

(72) Inventors: Chunlong Qiu, ShenZhen (CN); Xiao Zhang, ShenZhen (CN)

(73) Assignee: ShenZhen YiHong Holding Group CO., ShenZhen (CN)

() Term: 15 Years

(21) Appl. No.: 29/992,613

(22) Filed: Mar. 10, 2025

(51) LOC (15) Cl. 06-06

(52) U.S. Cl.

USPC D6/518; D3/307

(58) Field of Classification Search

USPC D3/205, 273, 274, 276, 277, 280, 282, D3/283, 289, 290, 304, 306, 307, 308,

D3/309, 313, 327; D6/518

CPC A61M 25/002; B65D 11/1833

(57) CLAIM

The ornamental design for a container as shown and described.

DESCRIPTION

FIG. 1 is a front, right, and above perspective view of a first embodiment of a container showing our new design;

FIG. 2 is a back, left, and below perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a front, right, and above perspective view of the container without its lid;

FIG. 10 is a perspective view of a second embodiment of a container with all features in all views identical to that of the first embodiment, except for being non-transparent; and,

FIG. 11 is a perspective bottom view thereof.

The broken lines depict portions of the container that form no part of the claimed design.

1 Claim, 8 Drawing Sheets
